The ornamental design for a display screen with graphical user interface, as shown and described.

DESCRIPTION

The file of this patent contains at least one drawing executed in color. Copies of this patent with color drawings will be provided by the United States Patent and Trademark Office upon request and payment of the necessary fee.

FIG. 1 is a front view of a first image of a display screen with graphical user interface showing our new design; FIG. 2 is a front view of a second image thereof; FIG. 3 is a front view of a third image thereof; FIG. 4 is a front view of a fourth image thereof; FIG. 5 is a front view of a fifth image thereof; FIG. 6 is a front view of a sixth image thereof; FIG. 7 is a front view of a seventh image thereof; FIG. 8 is a front view of a eighth image thereof; FIG. 9 is a front view of a ninth image thereof; FIG. 10 is a front view of a tenth image thereof; FIG. 11 is a front view of a eleventh image thereof; FIG. 12 is a front view of a twelfth image thereof; FIG. 13 is a front view of a thirteenth image thereof; FIG. 14 is a front view of a fourteenth image thereof; FIG. 15 is a front view of a fifteenth image thereof; FIG. 16 is a front view of a sixteenth image thereof; FIG. 17 is a front view of a seventeenth image thereof; FIG. 18 is a front view of an eighteenth image thereof; FIG. 19 is a front view of a nineteenth image thereof; FIG. 20 is a front view of a twentieth image thereof; FIG. 21 is a front view of a twenty first image thereof; FIG. 22 is a front view of a twenty second image thereof; FIG. 23 is a front view of a twenty third image thereof; FIG. 24 is a front view of a twenty fourth image thereof; FIG. 25 is a front view of a twenty fifth image thereof; FIG. 26 is a front view of a twenty sixth image thereof; FIG. 27 is a front view of a twenty seventh image thereof; FIG. 28 is a front view of a twenty eighth image thereof; and, FIG. 29 is a front view of a twenty ninth image thereof.

(Continued)

The appearance of the graphical user interface sequentially transitions between the images shown in FIGS. 1-29. The process or period in which an image transitions to another forms no part of the claimed design.

The broken line rectangle showing the display screen and the broken lines showing the graphical user interface illustrate portions of the display screen with graphical user interface that form no part of the claimed design.
